UNITED STATES PATENT OFFICE.

JAMES N. ECONOMOS, OF DAPHNE, ALABAMA.

OKRA MACHINE.

1,425,373.

Specification of Letters Patent. Patented Aug. 8, 1922.

Application filed November 15, 1921. Serial No. 515,307.

To all whom it may concern:

Be it known that JAMES N. ECONOMOS, a subject of the King of Greece, residing at Daphne, in the county of Baldwin and State 5 of Alabama, has invented new and useful Improvements in Okra Machines, of which the following is a specification.

The object of the invention is to provide simple and efficient means for heading and 10 cleaning okra without resorting to the tedious plan now in common use of handling the stems individually and manually and furthermore to provide means whereby the separation of the heads from 15 the whole okra may be accomplished and the latter may be cleansed or brushed to remove the fibres or "whiskers" with an efficiency which is impossible economically by the methods now in practice; and with these 20 objects in view the invention consists in a construction and combination of parts of which a preferred embodiment is shown in the accompanying drawings, wherein:—

Figure 1 is an elevation partly in section 25 of a machine embodying the invention.

Figure 2 is a plan view of the same.

Figure 3 is a vertical sectional view on the plane indicated by the line 3—3 of Figure 1.

Figure 4 is an enlarged detail sectional 30 view of the means for removing the okra heads.

Figures 5 and 6 are detail views of the cutter blades forming elements of the cutter mechanism.

Figure 7 is an enlarged detail sectional 35 view of the upper portion of the cleaning mechanism.

The apparatus embodies essentially the cutter mechanism 10 consisting of a plurality of units preferably arranged in a series and supported by a table 11 having lateral upstanding guards 12 upon which the okra may be placed in preparation for treatment, the series of cutters or headers being arranged adjacent to one edge of the table so as to be simultaneously accessible 40 to a number of operators occupying for example a bench 13 parallel therewith; means for conveying the okra from the cutting or heading mechanism as it is headed, and cleaning mechanism for receiving the okra from the conveyer and subjecting the same to a brushing apparatus and a blast 45 for the removal of dust, fibres or any other foreign matter including the so called "whiskers,"

In the construction illustrated the cutting or header mechanism consists of a plate 14 provided with openings 15 and 16 for the reception of okra heads, and preferably of 60 different sizes as indicated, and cutter plates 17 and 18 of which the former is reciprocably mounted in contact with the under surface of the plate 14 and between the same and the plate 18, with the latter secured to the 65 base plate 14 by bolts 19 extending through a longitudinal slot 20 in the reciprocable plate which is actuatable in one direction by a spring 21 having a tensioning bolt 22, and in the opposite direction by a cam 23 carried by a shaft 24. In the construction illustrated the plates 17 and 18 are provided with depending ears 17^a and 18^a for supporting the spring 21 of the tensioning device, and extending downward from the 70 openings 15 and 16, through which the okra heads are projected to be detached by the plate 17, is a carrier tube 25 provided at its upper end with a funnel 26 for receiving the heads as they are separated. The 75 carrier tubes 25 of the series of cutting or heading units deposit the heads upon a conveyer 27 which carries the same to a receptacle 28 at one end of the machine.

Obviously any suitable means may be employed for driving said shaft 24 and the conveyer, but in the construction illustrated a pulley 29 is attached to the shaft 24 which in turn is connected by bevel gears 30 with an upright shaft 31, and this in turn is 80 connected by bevel gears 32 which a horizontal shaft 33 carrying one end of the conveyer belt 27.

Adjacent to each cutting or heading device, and formed in the table top within convenient reach of the operator is an opening 34 for the reception of the whole okra, and leading from these openings are chutes 35 for conducting the okra to a conveyer 36 having an endless belt extending longitudinally of the frame of the machine and communicating with an elevator 37 also of the endless type by which the okra is conducted to and deposited upon a sieve 38 disposed at a rearward inclination and extending at 95 its rear edge under a hood 39. The sieve is designed to separate any loose dust or particles of foreign material from the okra, and to this end is mounted for reciprocatory movement on guides 40 and is actuated by 100 means of an eccentric 41 connected with the sieve by a pitman 42 and driven by a shaft 43

which receives its motion through gearing 44 from the shaft of one of the brush drums of which a plurality shown at 45, 46 and 47 are arranged in a suitable supporting frame 5 work 48 which also serves to support the sieve 38.

The hood 39 serves to prevent deflection of the okra as it passes from the sieve to a chute 49 by which it is conveyed to the 10 casing of the uppermost drum 45, said casing which is indicated at 50 being in communication by a chute 51 with a similar casing 52 of the drum 46 and which in turn is in communication by a chute 53 with the 15 casing 54 of the drum 47. Leading from the casing 54 is an outlet chute 55 to convey the okra to a storage bin or suitable receptacle and intercepting the chute 55 by means of suitable openings 56 in the walls 20 thereof is a blast of air produced by a fan 57 as a final means of removing any dust and fibre which may have been loosened by the passage of the okra through the several casings in which it is subjected to 25 the action of the drums.

The drums are of the brush type and operate in relation to breasts 45^a, 46^a and 47^a arranged in operative relation respectively with the drums and preferably mounted 30 for yielding movement toward and from the drums under the control of springs 58 which are adapted to be tensioned by suitable adjusting devices indicated at 59.

The means for communicating rotary motion 35 to the drums obviously may be variously constructed, a simple arrangement being illustrated in the drawing and consisting of belts 60 traversing suitable pulleys 61.

40 The effect of the apparatus as will be obvious from the foregoing description is to permit of the quick and effective removal of the heads and a thorough cleansing and conditioning of the whole okra including 45 the removal therefrom of any dust which may have been accumulated thereon in the growth or harvesting thereof to the end that the product is in a marketable condition when delivered at the outlet into the 50 receptacle or bin provided for its reception, and in this connection the manual handling of the material has been minimized to that incidental to presenting the heads to the cutting mechanism.

55 Preferably the plate 14 which forms an element of the cutting or heading mechanism is provided at the opposite end from the openings 15 and 16 with alternatively operative heads 15^a and 16^a which may be 60 arranged in position for use by reversing the plate, and may be made of a different size to adapt the same for different conditions of the product.

Also the surfaces of the cylinder or casing 65 breasts with which the brush drums co-

operate are preferably of corrugated rubber as indicated to afford a frictional or rubbing action which tends to effectively remove the fuzz or "whiskers" from the okra as it is necessary in order to prepare the 70 product for the market.

Having described the invention, what is claimed as new and useful is:—

1. An okra conditioning apparatus having the cutting or heading mechanism, a 75 cleaning mechanism for receiving and removing foreign matter from the whole okra, and separate conveyers for respectively receiving the heads and whole okra from the cutting mechanism, the latter of 80 which is arranged to convey to the okra cleaning mechanism.

2. An okra conditioning apparatus having the cutting or heading mechanism, a 85 cleaning mechanism for receiving and removing foreign matter from the whole okra, and separate conveyers for respectively receiving the heads and whole okra from the cutting mechanism, the latter of 90 which is arranged to convey to the okra cleaning mechanism, the cutting or heading mechanism consisting of a plurality of units, and chutes respectively related with 95 said units for conveying the heads and whole okra independently to separate conveyers.

3. An okra conditioning apparatus having the cutting or heading mechanism, a cleaning mechanism for receiving and removing foreign matter from the whole 100 okra, and separate conveyers for respectively receiving the heads and whole okra from the cutting mechanism, the latter of which is arranged to convey to the okra cleaning mechanism, the cutting mechanism having spaced stationary plates provided with registering openings for the reception of the okra heads, a cutter plate reciprocably mounted between said stationary plates and means for actuating the cutter 105 plate.

4. An okra conditioning apparatus having the cutting or heading mechanism, a cleaning mechanism for receiving and removing foreign matter from the whole 110 okra, and separate conveyers for respectively receiving the heads and whole okra from the cutting mechanism, the latter of which is arranged to convey to the okra cleaning mechanism, the cutting mechanism having spaced stationary plates provided with registering openings for the reception of the okra heads, a cutter plate reciprocably mounted between said stationary plates and means for actuating the cutter plate including a spring for imparting movement thereto in one direction and a rotary cam for imparting movement thereto in the opposite direction.

5. An okra conditioning apparatus hav-

ing the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cutting or heading mechanism having a reversible face plate provided with graduated head receiving openings and a continuously operable reciprocating cutter blade arranged to operate in the plane adjacent to one surface of said face plate and having a shearing action with relation to the openings therein.

6. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a preliminary shaker screen, rotary brush and cylinder abrading means for receiving the whole okra from the screen, and means for actuating said screen and brush.

7. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a preliminary shaker screen, rotary brush and cylinder abrading means for receiving the whole okra from the screen, and means for actuating said screen and brush, a directing hood being disposed in overlapping relation with the discharge end of the shaker screen.

8. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a preliminary shaker screen, rotary brush and cylinder abrading means for receiving the whole okra from the screen, and means for actuating said screen and brush, the screen being inclined downwardly from its receiving toward its discharge end for effecting the gravitational feeding of the okra.

9. An okra conditioning apparatus having the cutting or heading mechanism, a cleaning mechanism for receiving and re-

moving foreign matter from the whole okra, and separate conveyors for respectively receiving the heads and whole okra from the cutting mechanism, the latter of which is arranged to convey to the okra cleaning mechanism, the cleaning mechanism including a plurality of brushing devices each having a rotary brush and cooperative cylinder, with the cylinders arranged in series for effecting the successive presentation of the okra to the several brushes of the series.

10. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a plurality of brushing devices each having a rotary brush and cooperative cylinder, with the cylinders arranged in series for effecting the successive presentation of the okra to the several brushes of the series, the cylinders having movable breasts arranged in yielding relation with the brushes.

11. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a plurality of brushing devices each having a rotary brush and cooperative cylinder, with the cylinders arranged in series for effecting the successive presentation of the okra to the several brushes of the series, the cylinders having movable breasts arranged in yielding relation with the brushes and provided with corrugated faces.

12. An okra conditioning apparatus having the cutting or heading mechanism, a cleaning mechanism for receiving and removing foreign matter from the whole okra, and separate conveyors for respectively receiving the heads and whole okra from the cutting mechanism, the latter of which is arranged to convey to the okra cleaning mechanism, the cleaning mechanism including a plurality of brushing devices each having a rotary brush and cooperative cylinder, with the cylinders arranged in series for effecting the successive presentation of the okra to the several brushes of the series, the cylinders having movable breasts arranged in yielding relation with the brushes and provided with corrugated faces of frictional material.

13. An okra conditioning apparatus having the cutting or heading mechanism, a

cleaning mechanism for receiving and removing foreign matter from the whole okra, and separate conveyers for respectively receiving the heads and whole okra from the cutting mechanism, the latter of which is arranged to convey to the okra cleaning mechanism, the cleaning mechanism including a plurality of brushing devices each having a rotary brush and cooperative cylinder, with the cylinders arranged in series

for effecting the successive presentation of the okra to the several brushes of the series, the cylinders having movable breasts arranged in yielding relation with the brushes and provided with corrugated faces 15 of rubber.

In testimony whereof he affixes his signature.

JAMES N. ECONOMOS.
